UNITED STATES PATENT OFFICE.

JOSEPH SINKOVICH, OF BUTTE, MONTANA.

LOCK

1,036,156.

Specification of Letters Patent. Patented Aug. 20, 1912.

Application filed February 17, 1912. Serial No. 678,304.

To all whom it may concern:

Be it known that I, JOSEPH SINKOVICH, a citizen of the United States, residing at Butte, in the county of Silverbow, State of Montana, have invented certain new and useful Improvements in Locks; and I do hereby declare the following to be a full, clear, and exact description of the invention, such as will enable others skilled in the art 10 to which it appertains to make and use the same.

This invention relates to improvements in locks and more particularly to door locks of that type in which a pivoted tumbler is employed.

The principal object of this invention is to provide a lock of the character described in which means are provided for normally preventing the return of the lock bolt until 20 released by the key.

Another object of the invention is to provide a lock for the purpose described which includes a lock bolt, a spring actuated pawl pivoted on the shank of the bolt and normally disposed out of the path of movement of the key, and means adapted to be actuated by the key to release the pawl, and thereby cause the same to be disposed in the path of movement of the key, whereby upon 30 movement of the key against the pawl, the lock will be returned to its inoperative or initial position.

Another object of the invention is to provide a lock of the character described which is comparatively simple in construction, it being composed of a minimum number of parts, and is therefore cheap to manufacture.

With these and other objects in view, the 40 invention consists in the construction and novel combination of parts hereinafter fully described, illustrated in the accompanying drawings, and pointed out in the claims hereto appended; it being understood that 45 various changes in the form, proportion, size and minor details of construction within the scope of the claims, may be resorted to without departing from the spirit or sacrificing any of the advantages of the invention.

In the drawings: Figure 1 is a perspective view of a lock constructed in accordance with my invention, Fig. 2 is a front elevation of the lock, the parts being shown in 55 their initial positions, and the cover being removed to better disclose certain features

of the invention, Fig. 3 is a detail view of the lock mechanism showing the bolt partially extended, Fig. 4 is a similar view but showing the bolt in its extended position 60 and the pawl disposed in the path of movement of the key, Fig. 5 is a detail sectional view showing the pawl retained in its inoperative position by means of a spring detent, Fig. 6 is a detail view, partly in section, of 65 the outer and inner key cylinders, Fig. 7 is a detail top plan view thereof, Fig. 8 is a perspective view of the inner key cylinder, showing the cam arm for actuating the spring detent, and Fig. 9 is a perspective 70 view of the tumbler.

Like reference numerals designate corresponding parts in all the figures of the drawings.

Referring to the drawings, the invention 75 comprises a casing which is designated as a whole by the reference numeral 5 and mounted in the upper portion of said casing is a spring actuated latch-bolt 6 of ordinary construction. Located in the bottom portion of the casing is a thumb bolt 7 which is also of ordinary construction. Inasmuch as the latch bolt and thumb bolt are of common construction and form no part of this invention it is deemed that a specific description thereof is unnecessary.

Formed in one end wall 8 of the casing and intermediate the latch and thumb bolts is an opening 9 in which is slidably mounted the head 10 of a lock-bolt 11 sliding in a 90 suitable bracket 13 which is secured to the casing. This latch bolt is provided on its head with the usual stop 14, and on the upper edge of the shank 12 there is provided a plurality of notches 15. The lower edge 95 of the shank 12 is formed with the usual key sweeps 16, and the resultant talons 17.

Secured to the rear wall 18 of the casing and above the head 10 is a pin 19 to which one end 20 of a tumbler 21 is pivoted. This 100 tumbler includes a body portion 22 which normally extends longitudinally of and above the lock bolt 11, and has its end portion extended downwardly, as at 23, and thence forwardly as at 24, the free end 105 thereof extending forwardly, as at 25, and bearing against the body portion 22.

Formed in the angle between the body portion 22 and downwardly extending portion 23 is a lug 26 which is adapted to be 110 urged into any one of the notches 15 of the bolt by means of a flat spring 27, said spring

being fixed at one end to a post 28 which is carried by the casing. Associated with the casing is a cover plate 29, and this cover is formed with a key opening 30 which is disposed at a point in close proximity to the key sweeps 16, so that upon the insertion and rotation of a key 31, the talons 17 will be successively engaged to slide the lock bolt 11 outwardly in a step by step movement. It will be observed in this connection that there is preferably shown a pair of sweeps 16, and a pair of talons 17. Thus it will be obvious that in order to extend the bolt 11 to its limit, two manipulations or rotations of the key will be necessary. The keysweep 16 which is farthest away from the head 10 of the bolt is elongated, so that when the bolt is disposed in its operative or extended position, the reverse rotation of the key will not engage any sweep, and therefore the bolt will normally be locked by means of the tumbler against return movement. In order, therefore, to unlock the bolt or in other words to return the same to its inoperative or initial position, the following mechanism is employed: Secured to the lower rear end of the shank 12 of the bolt is a pin 32, and pivotally mounted upon this pin is a forwardly extending pawl 33. The forward end of this pawl forms a resultant talon 34, and this pawl is normally urged to swing downwardly upon the pin 32 so that the talon 34 will be disposed in the path of the key 31 by means of a flat spring 35 which has one end fixed to a post 36 carried by the bolt 11. In order to limit the downward movement of the pawl 33, there is provided a pin 37 which is carried by the bolt below the pivot pin 32.

In order to normally hold the pawl 33 out of the path of the key 31, said pawl is centrally formed with an opening 38 which registers with an opening 39 formed in the cover 29. A spring arm 40 is fixedly secured, as at 41, to the cover 29, and is disposed at one side of the key opening 30. The upper end of this arm is reduced to form an inwardly extending pin 42 which is normally disposed within the openings 38 and 39 above described. It will thus be observed that by means of this spring arm the pawl 33 is normally held out of the path of the key. In order, however, to release the pawl so that the spring 35 may urge the same into the path of the key so that the latter may engage the talon 34 of said pawl to return the bolt to its initial position, the following mechanism is employed: A key cylinder 43 projects laterally from the cover 29, and is secured to said cover by means of attaching feet 44 and 45 respectively, said feet being secured to the cover by bolts 46 or other suitable fastening means. The cylinder 43 registers

with the key opening 30, and is longitudinally slotted, as at 47, on its underside to permit of the head of the key projecting thereinto. The foot 45 has its major portion disposed in spaced relation to the cover and over the spring arm 40. The lower end 48 of the cylinder 43 is disposed in spaced relation to the cover 29. An inner key cylinder 49 is loosely mounted within the cylinder 43 for rotation therein, and the forward end of the inner cylinder projects beyond the forward end of the outer or stationary cylinder 43. The inner cylinder 49 is also longitudinally slotted, as at 50, this slot, however, being of less width than the slot 47 of the outer cylinder. Extending radially from the lower end of the inner cylinder 49 is a cam finger 51 which terminates at its outer end in an offset point 52. This finger projects between the lower end 48 of the outer cylinder 43 and the cover 29, and is adapted upon rotation of the inner cylinder 49 in one direction to be forced under the free end of the spring 40, and thereby withdraw the pin 42 from the opening 38 of the pawl 33, and thereby permit of the spring 35 to force said pawl downwardly into the path of movement of the key 31.

In order to actuate the inner cylinder by means of the key, said key is first drawn outwardly from engagement with the bolt 11, and is then given a slight twist to the right, the head of the key thus engaging the respective edge of the slot 50 and thereby causing the inner cylinder to be rotated until said edge is flush with the respective edge of the slot 47 of the outer cylinder. When the inner cylinder has assumed this position, the point 52 of the cam finger 51 will have shifted the spring arm 40 to release the pawl 33 as above described. The operator then returns the key to its operative position, and upon rotation thereof, the head of the key will be caused to engage the talon 34 of the pawl 33, and as a result, will shift the lock bolt 11 rearwardly for one step, and upon the next rotation of the key the respective talon 17 will be engaged to further return the bolt. It will be understood that as soon as the operator turns the key to the left, the head of said key will engage the pawl and raise the same to such a position as to permit of the pin 42 to be forced thereinto by means of the spring arm 40.

What is claimed is:

1. In a lock, the combination with a casing, of a bolt slidably mounted therein and formed with a plurality of talons adapted to be successively engaged by a key, of a spring actuated pawl pivoted on the bolt and adapted to be disposed in the path of movement of the key when the bolt is in its last successive position, a spring pin carried by the casing and adapted when the pawl is actuated upon the last movement of the key to

hold said pawl out of the path of movement of the key, and a rotary key-controlled means for actuating the pin to release the pawl.

5 2. In a lock, the combination with a casing, of a bolt slidably mounted therein and formed with a plurality of talons adapted to be successively engaged by a key, of a spring actuated pawl pivoted on the bolt and adapted to be disposed in the path of movement of the key when the bolt is in its last successive position, a spring pin carried by the casing and adapted when the pawl is actuated upon the last movement of the key to hold said pawl out of the path of movement of the key; a rotary key cylinder mounted on the casing, and a cam finger projecting laterally from the cylinder and adapted upon movement of the latter to engage and release the pin from the pawl.

10 3. In a lock, the combination with a casing, of a bolt slidably mounted therein and

formed with a plurality of talons adapted to be successively engaged by a key, of a spring actuated pawl pivoted on the bolt and 25 adapted to be disposed in the path of movement of the key when the bolt is in its last successive position, a spring pin carried by the casing and adapted when the pawl is actuated upon the last movement of the key 30 to hold said pawl out of the path of movement of the key, an outer key cylinder fixedly secured to the casing, a cylinder loosely mounted for rotation within the outer cylinder, a cam finger projecting laterally from the inner end of the inner cylinder and adapted upon rotation of the latter to actuate the spring pin to release the pawl.

15 In testimony whereof, I affix my signature, in presence of two witnesses.

JOSEPH SINKOVICH.
